United States Patent Office

Des. 229,000
Patented Nov. 6, 1973

229,000

BATHMAT

Robert O'Neil and Michael C. Wilson, Wheaton, Ill.,
assignors to Pretty Products, Inc., Coshocton, Ohio

Filed Sept. 10, 1971, Ser. No. 179,614

Term of patent 14 years

Int. Cl. D6—11

U.S. Cl. D6—209

FIG. 1 is a top plan view of a bathmat showing our new design;

FIG. 2 is an enlarged cross sectional view thereof taken on the line 2—2; and

FIG. 3 is an enlarged cross sectional view taken on the line 3—3.

We claim:

The ornamental design for a bathmat, substantially as shown.
